SUPPORTER GARMENT

Raymond M. Hoey, Chicago, Ill., assignor to The Kendall Company, Boston, Mass., a corporation of Massachusetts

Application September 21, 1946, Serial No. 698,456

2 Claims. (Cl. 128—160)

1

This invention relates to improved garments of the type comprising a pouch for retaining the genitals, elastic leg strap for maintaining the pouch in position and means for supporting the pouch and leg straps. Specifically, this invention has for its object the provision of improved garments of the athletic supporter type as distinguished from the suspensory type. The athletic supporter type of garment is illustrated and described in U. S. Patent #2,301,066, issued November 3, 1942, to Montmarquet. The suspensory type of garment is illustrated in U. S. Patent #722,121, issued to Lupfer, March 3, 1903. At the present time garments of the two distinct types are in commerce although the specific garment illustrated in Lupfer's patent is believed not available. At any rate the two types are recognized in the trade and sold as different items, athletic supporters being sold by sporting goods retailers, suspensories being sold usually only by drug stores. Both types of garments have pouches, leg straps and waist bands but differ widely in regard to functions, purposes, construction, materials, and appearance. Even where individual parts of suspensories have a superficial similarity to parts of athletic supporters, they usually are not interchangeable. For instance, the leg straps or cords which are illustrated in the Lupfer patent mentioned above are deceptively similar in outward appearance to the leg cords which are utilized in the products of this invention but the cords could not be substituted one for the other because their characteristics are different as will be fully explained hereinafter. The characteristics of the leg straps for a genital supporting garment are determined largely by the functions which the garment is designed to have.

Athletic supporters have the function of holding the male genitals in an unnatural protective position adjacent to and snugly contacting the lower abdomen. In order that this function may be comfortably operative, whether the wearer is at rest or engaged in violent physical action, it is necessary that certain maximum and minimum elastic tensions exist in the pouch and in the leg straps, particularly in the latter. The tension is quite critical in the leg straps, too little tension resulting in loss of supporter function and too much tension resulting in excessive binding, frictional irritation and burns of the skin. Inasmuch as athletic supporter leg straps have no other adjustment than the elasticity of the fabric of which they are made, it is important that the fabric have proper stretch characteristics. I have found that most satisfactory results are obtained when the leg straps are capable of being elongated, by the forces normally encountered in wear, a maximum of from 110 to 180%. More exactly a ten inch test length should, when subjected to the force of gravity on a weight of

2

from 55 to 80 ounces, extend to a maximum length of 21 to 28 inches. Furthermore, the maximum length should preferably not persist, due to hysteresis effect as weights are removed, beyond the point where 25 ounces remain suspended by the test length. In general the extended length should begin to decrease materially with from 35 to 25 ounces of weight remaining on the test length.

10 The purpose and function of suspensories are entirely different from those of athletic supporters. These devices are intended to alleviate a distressed condition. They are frequently used where the gonads are swollen and tender although they are also used where the scrotum is extremely elongated either as an after effect of disease or naturally as is characteristic of certain races. Suspensories are intended to permit persons with the above mentioned conditions and others to suspend the gonads in a comfortable position similar to the normal position they occupy in most males. It is axiomatic that such devices have very little tension in the leg straps, natural non-binding cradling support being the desired objective. The leg straps of such devices are usually narrow because they are not designed to withstand heavy stresses. Usually they are mechanically adjustable and very frequently are not elastic. Those suspensories which do have elastic leg straps in general have straps which are capable of being extended a maximum of 50 to 80% although the forces normally encountered in usual wear are insufficient to provide maximum extension. A ten inch test length of 20 the average suspensory leg strap material when subjected to the force of gravity on a weight of from 55 to 80 ounces will extend to a maximum length of from 15 to 18 inches. The hysteresis effect on such material is marked, material reduction in length upon successive removal of 25 weights not occurring until only 17 to 12 ounces remain suspended by the test. It is evident from the above that leg straps of suspensories are not interchangeable with leg straps of athletic supporters because of insufficient elongation and lack of tension in the former. Previous to this invention it was considered essential to the attainment of the desired stretch characteristics in athletic supporters that relatively wide, loosely-woven leg straps be provided in contrast to the comparatively narrow, fairly tightly-woven type of strap provided in suspensories. But the type of leg straps utilized in athletic supporters hitherto has certain disadvantages 30 enumerated hereinafter which I have found are largely incidental to their width and which are substantially eliminated by the leg straps of the products of this invention.

Leg straps of supporters must of necessity be highly conformable in that they must conform

to the three dimensional curves of the lower body trunk. But good conformability has not always been possible with wide leg straps because of the difference in length of the edges of the strap necessary to completely conform. With wide straps one edge of the strap may be in a stretched condition while the other is so slack as to wrinkle and curl out of snug contact with the body. Nor are such straps ideally suited to bear the severe stresses to which leg straps of athletic supporters are normally subjected because stresses are not properly equalized throughout the width of the strap. Some elastic threads, particularly at the side edges, bear a far heavier load than others, so that frequently side threads break, causing unsightly crimping and crinkling of the fabric and impaired functionality in the supporter. The higher stresses to which these leg straps are subjected are intensified by the fact that the straps are securely fastened to the bottom of the pouch so that the part so fastened is held in restricted relationship with respect to the body when stresses are encountered. The phrase "in restricted relationship" is used advisedly because undoubtedly the pouch itself stretches and in addition is pulled toward the leg strap under tension. In actual use, therefore, the pouch bottom on the presently known type of athletic supporter is pulled from side to side on the body as the stress becomes greater on first one leg strap and then the other. This movement of the pouch, which is insufficient to relieve the higher stresses, causes discomfort to the wearer and, in addition, causes the lower edges of the pouch to roll and curl.

My invention provides for the first time a pouch and leg straps which are parts of a complete garment suitable for athletic wear, which parts do not have the disadvantages hitherto encountered. The objectionable features have been overcome by providing a new type of leg strap in the form of a cord with the requisite stretch characteristics for athletic supporter straps. I have discovered that a cord substantially circular in cross section will provide a more conformable strap and one in which a more even distribution of stresses in use occurs. In such cords, the elastic threads are concentrated so that they act more or less as a unit, each of the elastic threads bearing a more nearly equal share of the total load with no individual thread so heavily burdened as to break during normal use. Furthermore, such cords need not be relatively fixed to the pouch bottom. I have found that a slip loop may be provided at the pouch bottom through which the cord is threaded and that even under considerable stresses the cord will readily render through the slip loop. This construction, although it otherwise would be distinctly advantageous, is not practical with wide ribbon-like straps because such straps fold over and bunch at the slip loop. This invention provides the first athletic supporter having slip loop construction, permitting both leg straps to be parts of a continuous elastic cord, the stresses on which are fairly equalized throughout the cord length.

Referring to the drawings

Figure 1 is a front view of a preferred form of the invention as embodied in an athletic supporter.

Figure 2 is a perspective detail of the lower portion of the pouch of Figure 1 with the attached slip loop and a portion of the leg cord.

Figure 3 is a cross section of the preferred leg cord of Figure 1 showing its constructions.

In Figure 1, 10 is an elastic waist band supporting the formed supporter pouch 11 and the elastic leg cord 12. At the bottom portion of pouch 11 is fastened, by stitching 13, a tape formed into a slip loop 14. Elastic leg cord 12 which is threaded through slip loop 14 and is free to move in reciprocating motion therethrough, is fastened at its ends by stitching 15 to waist band 10.

In Figure 3 preferred leg cord 12 is shown in cross section to be formed of a plurality of individual rubber threads 16 united by a figure 8 inner thread covering 17 and surrounded by an outer braided thread covering 18.

While the preferred type of garment which is embraced by this invention is that illustrated in the drawings, this invention is in no way limited to that particular embodiment. Nor is the invention limited to the particular construction of the slip loop or of the cord illustrated as preferred. Other constructions which utilize cords substantially circular in cross section having the proper stretch characteristics either alone or in conjunction with various types of slip loops are within the scope of the invention.

I claim:

1. A compressive athletic supporter comprising an elastic waistband, an elastic pouch affixed along its upper portion to the front of said waistband and two segments of longitudinally extensible and elastic cord, constituted of a series of compact longitudinally extending elastic threads, permanently and non-detachably connecting the bottom portion of said pouch to the waistband and forming elastic leg straps for the supporter, said cord being substantially only as wide as it is thick so that the elastic threads of said cord bear substantially equal proportions of loads placed on said cord and a ten inch length thereof being extensible to from twenty-one to twenty-eight inches when subjected to the pull of fifty-five to eighty ounces of weight.

2. A compressive athletic supporter comprising an elastic waistband, an elastic pouch affixed along its upper portion to the front of said waistband, a slip loop attached to the bottom of said pouch and a longitudinally extensible and elastic cord, constituted of a series of compact longitudinally extending elastic threads, threaded through said slip loop and free to move in restricted reciprocating motion therethrough, permanently and non-detachably connecting the bottom portion of said pouch to the waistband and forming elastic leg straps for the supporter, said cord being substantially only as wide as it is thick so that the elastic threads of said cord bear substantially equal proportions of loads placed on said cord and a ten inch length thereof being extensible to from twenty-one to twenty-eight inches when subjected to the pull of fifty-five to eighty ounces of weight.
